UNITED STATES PATENT OFFICE.

DAVID D. GORDON, OF CHICAGO, ILLINOIS, ASSIGNOR TO THE YOST ELECTRIC MANUFACTURING COMPANY, OF TOLEDO, OHIO, A CORPORATION OF OHIO.

ELECTRIC-SWITCH MECHANISM.

1,220,414.

Specification of Letters Patent. Patented Mar. 27, 1917.

Application filed May 13, 1916. Serial No. 97,264.

To all whom it may concern:

Be it known that I, DAVID D. GORDON, a citizen of the United States, and a resident of Chicago, in the county of Cook and State of Illinois, have invented a certain new and useful Electric-Switch Mechanism; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to electric switches, and particularly to those of the quick make and break type.

The object of my invention is the provision of an improved electrical switching mechanism of the class described, which is compact in form, simple and comparatively inexpensive in construction, and highly efficient in operation. Other objects and advantages of the invention will be apparent from the following detailed description thereof.

While the invention, in its broader aspect, is capable of embodiment in numerous forms, a preferred embodiment thereof is illustrated in the accompanying drawings, in which—

Figure 1 is a side elevation of a switch embodying my invention in open position and with the inclosing case therefor in section. Fig. 2 is a plan view thereof with the top part of the inclosing case removed. Fig. 3 is a reduced section on the line *w-w* in Fig. 2, with the circuit wires removed. Fig. 4 is a reduced edge view of the case inclosing the switch with the circuit wires leading therein. Fig. 5 is an enlarged perspective-view of the bridging or switch member of the switch mechanism. Fig. 6 is a perspective view of the thrust bar for the bridging member, and Fig. 7 is a perspective view of the control bar of the switch.

Referring to the drawings, 1 and 2 designate what may be termed the base or cap parts of a case or body member in which the switch mechanism comprising the invention is located, said parts preferably being composed of insulating material. These case parts form an interior chamber 3 in which the switch mechanism is disposed and which has an opening 4 in each end. It will be

understood, however, that my invention is not limited to the use of any particular form or type of case.

Plates 5, 5 are mounted in respective recesses 6, 6 in the opposite walls of the chamber 3, and each carries a binding screw 7 for attaching a terminal wire to the plate. A yielding contact finger 8, of L-form in the present instance, projects from each plate 5 into the chamber 3 and an electric circuit is bridged across from one to the other of these contact fingers by a bridging or switch member 9 when in contact therewith.

The switch member 9, in the present instance, comprises two parallel side bars 10, 10 and the connecting pieces 11 and 12. The member 9 is intended to have rocking movements in the chamber 3, to place the forward ends of its side bars 10, 10 into and out of contact with the contact fingers 8, 8, and for such purpose is provided at opposite sides thereof near its rear end with trunnion parts 13, 13, which, in the present instance, are mounted in recesses 14, 14 provided in the respective side walls of the chamber 3 at the top edge of the base part 1 of the case. The trunnions 13, in the present instance, are struck outward from the upper edge portions of the respective bars 10 and rounded on their bottom edges to form suitable trunnion parts.

The connecting piece 11 of the bridging member connects the lower edges of the bars 10, 10 and extends forward from the rear ends thereof to a point in advance of the rocking axis of the switch member, but in spaced relation to the forward end thereof, as shown. The rear end of the connecting piece 11 is preferably turned up, as shown at 11a. The connecting piece 12 is disposed in upright position in advance of the rocking axis of the bridging member, and, in the present instance, substantially midway of the ends of the switch member. An opening 15 is provided through the connecting piece 12 and has a spur 16 projecting therein from one side thereof in spaced relation to and midway of its top and bottom walls.

A control-bar 17 projects through the chamber 3 between the two openings 4, 4 thereof and carries a head or push-button 18 at each end for reciprocatory movement in the respective opening 4. This bar extends through the opening 15 in the switch member connecting-piece 12, and in width is sub-

stantially equal to the width of said opening and has one edge thereof of suitable depth to have free longitudinal movements between either of the spaces provided between 5 the spur 16 and the top or bottom wall of the opening 15. The spur 16 is intended to coact with the adjacent edge of the bar 17 to prevent rocking movements of the bridging member until either one of a pair of 10 recesses 19 has been moved into register therewith, the bridging member being then permitted to rock transversely of the bar 17 by reason of the spur 16 passing through the registering notch 19 in the bar.

15 The means employed for imparting quick rocking movements to the bridging member, when released for such purpose by a movement of one of the notches 19 in the control part 17 into register with the spur 16, will 20 now be described. A thrust-bar 20 is carried by the bar 17 with its lower end projecting loosely through an opening 21 in said bar and bearing downward against the cross-piece 11 of the bridging member, which 25 cross-piece may for convenience be termed the thrust plate of the bridging member. The downward movement of the bar 20 through the opening 21 is limited by spurs 22 projecting transversely from said bar and 30 coacting with the top side of the control-bar 17. The upper end of the bar 20 projects loosely into an opening 23 provided in the top portion of a frame-piece 24, which is mounted within the chamber 3. A coiled 35 compression spring 25 encircles the bar 20 and has its respective ends thrust against the spurs 22 on the bar and the frame-piece 24, thereby normally urging a downward movement of the thrust-bar. A longitudinal 40 shifting of the control-bar 17 will cause a movement of the lower end portion of the thrust-bar 20 from one side to the other of the rocking axis of the switch member, and during this movement the lower end of the 45 thrust bar slides up the inclined thrust-plate 11 of the bridging member, and is also moved upward with respect to the control-bar 17 to effect a compressing of the spring 25. When the lower end of the thrust bar 50 20 has moved a predetermined distance past the rocking axis of the switch member the energy stored in the thrust-bar by the spring 25 will cause a quick downward rocking movement of the end of the switch toward 55 which the thrust-bar is being moved and effect either a quick breaking or a quick closing of the circuit between the contact fingers 8, 8 by the switch member.

The frame-piece 24 preferably comprises 60 a strip of bar metal which extends around a portion of the chamber 3 lengthwise thereof and has portions forming guides through which the control-bar 17 has reciprocatory movements. The parts of the 65 frame-piece through which the control-bar

projects also serve as stop means with which the heads or push-buttons 18 may coact to limit the reciprocatory movements of said bar, as is apparent.

The operation of my improved switch is 70 as follows: Should the switch parts be in the open position shown in Fig. 1 and it is desired to move the switch member into circuit closing contact with the fingers 8, 8, the operator moves the control-bar 17 to the right, thereby forcing the lower end of the thrust bar 20 up the inclined thrust plate 11 of the bridging member toward the elevated right hand end thereof. Such movement of the thrust-bar 20 causes it to move upward 80 against the tension of the spring 25. When the control-bar 17 has moved a sufficient distance to place the left hand notch 19 therein in register with the spur 16, the lower end of the thrust-bar 20 will have passed the 85 rocking axis of the bridging member and will cause a quick downward rocking movement of the switch member to place the forward ends of the bars 10 thereof into contact fingers 8, 8. When the switch member 90 has rocked to this position the spur 16 will have moved through the registering notch 19 and to a point below the bar 17 so that upon a reverse movement of the control-bar 17 the spur 16 will coact with the under side 95 of the bar 17 and prevent an upward rocking of the switch member until the lower end of the thrust-bar 20 has been moved back past the rocking axis of the switch member and the spur 16 has moved into register with the other notch 19 in the control bar. It is thus evident that the reciprocatory movement of the control-bar 17 not only causes a release of the switch member 100 to permit rocking movements of the switch member in first one direction and then the other at predetermined points in a movement of the control bar, but also shifts the lower end of the thrust bar 20 in first one direction and then the other past the rocking axis of the switch member, whereby the downward pressure exerted on said thrust-bar by the spring 25 actuates the rocking movements of the switch member. 105

I wish it understood that my invention is 110 not limited to any specific construction, arrangement or form of the parts, as it is capable of numerous modifications without departing from the spirit of the claims.

Having thus described my invention, what 115 I claim as new, and desire to secure by Letters Patent, is—

1. In an electric switch, a bridging element mounted for rocking movements, a control member reciprocally movable transversely of the axis of said element, said element and member having parts which coöperate to prevent movements of said element except when said member is at predetermined points in its reciprocatory move- 120 125 130

- ments, and thrust means shiftable with respect to said element by movements of said control member and operable to rock said element in one direction when the control member is at a predetermined point in one direction of movement thereof, and vice versa.
2. In an electric switch, spaced contacts, a bridging element mounted for oscillatory circuit making and breaking movements relative to said contacts, a reciprocatory control member coacting with said element to prevent rocking movements thereof except when at predetermined points in its movements, and thrust means shiftable by said member with respect to said element and operable to actuate movements of said element in first one direction and then the other when successively released for movement by said member.
3. In an electric switch, spaced contacts, a bridging element mounted for rocking movements with respect to said contacts to make and break connection therewith, a control bar mounted for reciprocatory movements transversely of the rocking axis of said element, said element and bar having parts which coöperate to lock the element against movement except when the bar is at different predetermined points in its movement, and thrust means shiftable by movements of said bar and acting on said element transversely of the bar to effect a rocking movement of the element first in one and then the other direction when successively released for such movements.
4. In an electric switch, a bridging element mounted for rocking movements, a reciprocatory control bar movable transversely of the rocking axis of said element, said bar coöperating with said element to prevent rocking movements thereof except when said bar is at spaced predetermined points in its movement, oscillatory thrust means in thrust contact at its swinging end with said element and shiftable lengthwise of the element by movements of said bar to exert pressure on said element first at one side, and then the other of its axis.
5. In an electric switch, a bridging element mounted for rocking movements, and having a thrust plate extending lengthwise thereof in tangential relation to a circle struck from the rocking axis of said element, reciprocally movable means coöoperating with said element to prevent rocking movements thereof except when the means is at different predetermined points in its movements, and thrust means acting on the thrust plate of said element and shiftable lengthwise thereof by movements of said control means, whereby an element rocking thrust is exerted on said plate first at one side and then the other of the rocking axis of the element.
6. In an electric switch, a bridging element mounted for rocking movements and having a thrust receiving part extending from one side to the other of its axis and disposed in tangential relation to a circle struck from such axis and also having a part provided with an opening with a spur projecting therein from one side wall of the opening, a control bar extending lengthwise of said element transversely of its axis and through said opening, said bar having spaced notches which successively move into register with said spur when the bar is at different points in its movement, and thrust means acting against the thrust receiving part of said element and shiftable from one side to the other of the element axis by movements of said bar.
7. In an electric switch, a bridging element mounted for rocking movements and having parts forming side bars, a thrust part and a part forming a guide opening, said side bars having trunnions projecting outwardly therefrom above said thrust part, a reciprocatory control bar mounted for movements lengthwise of said element and through the guide opening thereof, said bar and element having parts which coact to prevent rocking movements of the element except when the bar is at different predetermined points in its movement, a thrust bar disposed transversely of said control bar and pivotally mounted at one end and having its other end projecting through a part of said control bar and in thrust contact with the thrust part of said element, said thrust bar being shiftable lengthwise of said element and from one side to the other of its axis by movements of said control bar, and means acting on said thrust bar to yieldingly force it into contact with said element, whereby rocking movements are imparted to the element first in one direction and then the other as the position of said thrust bar is shifted from one side to the other of the element axis and the element is released for such movements by said control bar.

In testimony whereof, I have hereunto signed my name to this specification.

DAVID D. GORDON.
